UNITED STATES PATENT OFFICE.

HULDREICH KELLER, OF BERLIN, GERMANY, ASSIGNOR TO GENERAL ELECTRIC COMPANY,
A CORPORATION OF NEW YORK.

AIR PUMP OR CONDENSER.

No. 922,595.

Specification of Letters Patent.

Patented May 25, 1909.

Application filed January 23, 1907. Serial No. 353,615.

To all whom it may concern:

Be it known that I, HULDREICH KELLER, a citizen of Switzerland, residing at Berlin, Germany, have invented certain new and 5 useful Improvements in Air Pumps or Condensers, of which the following is a specification.

My invention relates to a device for pumping or conveying, and compressing or conveying 10 fluids wherein a denser fluid or medium is made to compress or condense fluids of lesser density. The denser fluid flows or is conveyed in any suitable manner to a rotating member of the device. Centrifugal 15 action throws the fluid outward into a surrounding member, and its outward flow is so interrupted that the fluid forms a continuous series of spaced fluid masses which have a piston-like action on the less dense 20 fluid. If the denser fluid be water and the less dense fluid be steam, a condensation of the steam will also occur when the two fluids are brought together in the outer member.

The object of my invention is the provision 25 of a simple and efficient device for performing the operations described, in which the rotary member has separate channels or conduits for the two fluids, a construction which makes it possible to design each set of 30 channels or conduits to suit the particular characteristics of the fluid to be conveyed thereby.

In the accompanying drawing, showing an 35 illustrative embodiment of my invention, Figure 1 is a partial sectional view with the plane of the section perpendicular to the axis of the machine; and Fig. 2 is a section through the rotary and stationary members of the machine, substantially at right angles 40 to the plane of the section in Fig. 1.

The rotary member or impeller wheel 1 is mounted upon a shaft 2 driven in any suitable manner. Surrounding the wheel is a directing ring or member 3. A casing 4, 45 only a portion of which is shown in the drawing, incloses the mechanism just described, supporting the ring 3, affording bearings for the shaft 2, and providing suitable channels or conduits for the entrance of the two fluids 50 and for the exit or discharge of the resultant fluid.

A conduit 5, for supplying water or other fluid to the wheel 1, is shown in the drawing. This conduit leads to a series of outwardly directed conduits or passages 6 in the impeller wheel 1. The cross-section of the passages 6 is gradually reduced from the inlet to the outlet but the shape of said passages may be varied to suit the operating conditions to be met by a given machine. The sides of the 60 passages 6 are inclosed by suitable walls 7 which also form the faces or sides of the wheel. Extending from one wall 7 to the other are walls or partitions 8 which form between them the passages or buckets 6 and 65 another set of conduits or passages 9 which alternate with the passages 6 around the circumference of the impeller wheel. The walls or blades 8 are grouped in pairs with their ends toward the shaft united to form a 70 sharply defined edge between the entrances to the passages 6. Beyond this edge, the walls separate to form the passages or buckets 9. Openings 10 in the sides of the wheel communicate with the passages 9. The 75 outer ends of the walls 8 are supported by portions 11 of the wheel rim which span the openings 10 but leave a clear outward passage. Curved passages or conduits 12 are formed between the partitions or blades 13 80 of the directing ring 3. The curvature of these passages is opposite to that of the passages 6. A small clearance space 14 is provided between the rim of the wheel 1 and the directing ring 3. 85

As the impeller wheel 1 is rotated in the direction of the arrow, Fig. 1, water or other fluid entering the passages or buckets 6 from the conduit 5 is thrown outward by centrifugal action into the passages or buckets 12, 90 but because of the interruption of the connection between the passages or buckets 6 and 12, separated columns or masses of water 15 are formed in the conduits 12. Between these fluid masses 15 are portions of 95 air, steam or other fluid which are drawn through the openings 10, passages 9 and the space 14, from the space surrounding the wheel and the conduit 5, and are forced outward by the piston-like action of the fluid 100 masses 15. The discharge from the passages 12 is collected in a suitable portion of

the surrounding casing and is disposed of as desired.

The arrangement described is very efficient and simple, having no valves or reciprocating parts. The moving member has a rotary motion, and is provided with separate passages for the two fluids so that they are efficiently handled and brought together only in the directing member where the compression or condensation occurs.

In accordance with the provisions of the patent statutes, I have described the principle of operation of my invention, together with the apparatus which I consider to represent the best embodiment thereof; but I desire to have it understood that the apparatus shown is only illustrative, and that the invention can be carried out by other means.

What I claim as new and desire to secure by Letters Patent of the United States, is,—

1. The combination of a rotary impeller having separate sets of fluid discharging passages, with a casing; a member located within the casing and surrounding the periphery 25 of the impeller that is provided with passages which receive fluid first from one set of passages in the impeller and then from another set as the periphery of the impeller moves past the inlet openings of the passages 30 in said member.

2. The combination of a rotary impeller having separate sets of fluid passages arranged in multiple, each set receiving and discharging a different fluid, with a stationary casing inclosing the impeller and having a member provided with passages to which the different fluids discharged from the sets of passages in the impeller are successively delivered to form streams composed of successive masses of said fluids.

3. The combination of an impeller having a set of passages which receive fluid near the axis of the impeller and discharge it outwardly, and a second set of passages which receive fluid from openings arranged in multiple and discharge it outwardly, and a member having passages which receive fluid first from one set of impeller passages and then from the other.

4. The combination of an impeller having two separate series of fluid passages leading to two series of alternating openings or outlets in the periphery of the impeller, and a directing member adjacent said periphery 55 having a series of fluid passages coöperating with the impeller passages to receive the discharge therefrom, the member and the impeller being relatively rotatable.

5. The combination of a rotatable impeller, a fluid-supply conduit adjacent the center of the impeller, conduits in the impeller leading from the supply conduit to openings in the circumference of the impeller,

other and separate conduits in the impeller leading from a separate source of fluid-supply 65 to separate openings in the circumference of the impeller which alternate with the first set of openings, a directing member adjacent the impeller circumference, and conduits in said member which receive the fluid discharged by centrifugal action from the openings or outlets in the circumference of said impeller.

6. The combination of an impeller provided with a series of alternating conduits 75 leading from separate inlets in its hub and face respectively to separate outlets in its circumference, with a directing ring concentric with the impeller, conduits in the ring, and means for rotating the impeller to interrupt the delivery of fluid from the outlets to the conduits in the ring.

7. The combination of an impeller, a supply conduit adjacent the center of the impeller, a series of conduits leading from the supply conduit to the circumference of the impeller, a separate series of conduits between the openings in the face of the impeller and openings in its circumference, a directing ring adjacent the circumference of the impeller, and a series of conduits in the ring coöperating with the impeller conduits, the impeller and the ring being relatively rotatable.

8. The combination of an impeller, a series 95 of inlets adjacent the center of the impeller, a series of inlets in the face of the impeller, alternating series of outlets in the impeller circumference, a separate series of conduits joining each series of inlets with one of the 100 series of outlets, a directing member surrounding the impeller, and a set of conduits in the member coöperating with the outlets in the impeller circumference, the impeller and the member being relatively rotatable. 105

9. The combination of an impeller, conduits extending from adjacent the center of the impeller to its periphery, walls for said conduits extending transversely to lateral faces of impeller, conduits formed in said 110 walls which lead from openings in the face of the impeller to outlets in its periphery, and a directing member surrounding the impeller.

10. The combination of a shaft, an impeller wheel having a hub mounted on the shaft, an annular flange projecting parallel to the shaft from one side of the hub and having a series of openings on the inside thereof, two spaced circular flanges on the periphery of the first flange substantially at 120 right angles to the axis of the shaft, conduits leading from said openings to outlets in the circumference of the impeller, said conduits being formed by walls extending across the space between the two flanges, conduits 125 formed in said walls which lead from inlet

openings in the outer faces of the flanges to outlets in the circumference of the impeller that alternate with the outlets of the first series of conduits, and a directing member 5 surrounding the impeller having conduits which receive the discharge from the conduits in the impeller.

In witness whereof, I have hereunto set my hand this 5th day of January, 1907.

HULDREICH KELLER.
